John Graves

UNITED STATES PATENT OFFICE.

JOHN GRAVES, OF GREEN POINT, NEW YORK.

WHIFFLETREE.

SPECIFICATION forming part of Letters Patent No. 295,866, dated March 25, 1884.

Application filed August 4, 1883. (No model.)

To all whom it may concern:

Be it known that I, JOHN GRAVES, of Green Point, county of Kings, and State of New York, have invented a new and useful Improvement in Whiffletrees; and I hereby declare that the following is a full and exact description of the same, referring to the annexed drawings.

The object of my invention is to obtain a strong, durable, and elastic whiffletree.

In order that anybody may understand my invention, I will describe the same.

The accompanying drawings form a part of the specification.

15 Figure 1 shows a piece of sheet metal from which the whiffletree is formed. Fig. 2 shows a side view of the whiffletree after being formed. Fig. 3 shows a top view of the formed whiffletree. Fig. 4 is an end view of the whiffletree.

Similar letters of reference indicate like parts.

In making my whiffletree, I take one or more plates of sheet metal, and form the same in a trough-like form and corrugate the edges, as shown in Fig. 2. The corrugations extend from the edge inward toward the center line; but a considerable portion of the back is plain or not corrugated, as shown in Fig. 3. The 30 same time that I bend the corrugated edges up I bend the top of them over to the outside, as shown in Fig. 4.

By means of the corrugations and the turned-up sides and turned-out edges I obtain great 35 strength, elasticity, and durability without a great amount of metal.

When my corrugated whiffletree is fastened to a wagon or horse-car and the same is heavy loaded, it will take the whole strain, will relieve the horses by its spring and elastic motion, and will receive the greatest, if not the whole, part of the blows, jars, or sudden strain. When the horses start a loaded vehicle, the whiffletree will form itself more in a half-circle shape, and the corrugation *a a* will contract, 40 and as soon as the strain is off the whiffletree the same will come back to its former shape and the corrugation will somewhat draw out. In the plain part *b* in the center a hook or ring is fastened; or any other known device may 45 be used to fasten it to the vehicle or horse-car.

Great strength and elasticity are obtained by my corrugated whiffletree without breaking and without overstraining any part of it, the edges being turned up or down, and the edges 50 of the turned-up sides being turned outward, as shown at *a*, Fig. 4.

What I claim as my invention is—

A corrugated whiffletree made of one or more sheet-metal plates, with the sides turned 60 up or down and the edges of the turned-up sides bent outward, as and for the purpose set forth.

Sealed and delivered this 16th day of June, 1883.

JOHN GRAVES. [L. S.]
